H. A. DOUGLAS

CIRCUIT CONTINUING DEVICE

Filed April 17, 1922

Inventor
Harry A. Douglas
By G. A. Gray
Atty.

UNITED STATES PATENT OFFICE.

HARRY A. DOUGLAS, OF BRONSON, MICHIGAN.

CIRCUIT-CONTINUING DEVICE.

Application filed April 17, 1922. Serial No. 554,268.

My invention relates to circuit continuing devices and will be fully explained in connection with the accompanying drawing.

Fig. 1 is a longitudinal sectional view illustrating enough of a headlighting or other reflecting lamp constructed in accordance with the invention and Fig. 2 is a view in elevation.

The plug 1 carries spring pressed contacts 4 that project from spring barrels 2 said plug being receivable in a shell 11 upon a sufficient depression of the pins 5, that are carried by the plug into the plug. These pins, instead of engaging the usual bayonet slots in the shell are snugly receivable in the formations or passages 12 in the shell whereby the shell and plug are prevented from having material relative movement. When the plug has been assembled with the shell by the reception of the pins 5 in the openings 12 each contact 4 is in position to be engaged by the complementary contact upon the inner end of the base of an inserted incandescent lamp which carries bayonet pins receivable within slots 16. When the circuit continuing device is embodied in a reflecting lamp structure the reflector 17 of the lamp has a rearwardly extending cylindrical holder 18 which is provided with an opening or passage 19. The shell 11 is received in the holder, one of the pins 5, preferably longer than its companion, projecting into the passage 19 whereby this pin not only effects assembly between the plug or contact carrier 1 and the shell 11 but also effects assembly between the shell and holder. As illustrated, the holder 18 extends longitudinally of the lamp axis and in order that the incandescent lamp held in the forward end of the shell 11 may be focused, the opening 19 is elongated and extends longitudinally of the holder to permit the shell and the parts assembled therewith to be moved longitudinally of the lamp axis and with respect to the holder. It will be seen that the hollow holder 18 is cut away opposite slot 19 to

provide a clear space, the shell 11 having its two opposite openings 12 in register with said slot and clear space. The plug received in shell 11 has an opening extending transversely therethrough and in register with the aforesaid slot, clear space, and the opposite openings in the shell, said opposite openings being narrower than the transverse opening in the plug. The pins 5 are headed and their shanks pass through the opposite openings in the shell. The pin heads are larger than these openings and engage the inner side of the shell. The single spring 10 is received in said transverse opening in the plug and presses outwardly upon said pins.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

A circuit continuing device including a hollow holder having a longitudinal slot in one side and cut away opposite said slot to provide a clear space; a shell received in said holder and having two opposite openings in register with said slot and clear space; a plug received in said shell and having an opening extending transversely therethrough and in register with the aforesaid slot, clear space, and the opposite openings in the shell, said opposite openings being narrower than the transverse openings in the plug; headed pins whose shanks pass through said opposite openings in the shell and whose heads are larger than these openings and engage the inner side of the shell; and a single spring received in said transverse opening and pressing outwardly upon said pins.

In witness whereof, I hereunto subscribe my name this 26th day of March A. D., 1920

HARRY A. DOUGLAS.
